STEPLADDER, TRESTLE, AND THE LIKE

John Allan, St. Kilda, Victoria, Australia

Application June 22, 1944, Serial No. 541,588
In Australia August 28, 1943

11 Claims. (Cl. 228—29)

This invention relates to improvements in step ladders and the like—that is to say, ladders of the type having a forward portion provided with steps or rungs and a rearward portion which constitutes a prop and which is hingedly connected at its upper end to the upper part of the front or stepped portion.

More particularly the aforesaid prop usually comprises a spaced pair of legs rigidly connected together, the spacing of such legs being approximately the same as the spacing of the legs or side members of the front or stepped portion of the ladder.

Thus in use the step ladder is supported at four mutually spaced points and, in order that it may be safe and stable in use, it is necessary to arrange these four points or legs substantially in the same horizontal plane. Accordingly, when such a ladder is mounted on an uneven surface, it is generally necessary to place a wedge or equivalent packing below one or more of the legs.

Now, the general object of this invention is to provide improvements in step ladders and the like while a more specific object is to provide a step ladder of simple and effective construction which will overcome or minimise the abovementioned disadvantages of step ladders at present in use. Yet another object is to provide a step ladder having an adjustable prop capable of being located close to a reentrant corner.

Accordingly the invention broadly resides in a step ladder, trestle or the like having a front portion and a supporting prop, said prop comprising a longitudinally disposed member, means pivotally connecting the upper end of the longitudinally disposed member to an upper part of the front portion, a cross member pivoted intermediate its ends to the longitudinally disposed member, a pair of prop legs arranged one at each side of the longitudinally disposed member and pivotally connected to said rigid member, link means spaced from said cross member, and means for maintaining said longitudinally disposed member in a plane substantially parallel to the plane of the prop legs.

The said link means is preferably so formed or arranged as to provide a guide slot for the adjacent portion of the longitudinally extending member. Preferably the longitudinally extending member and an intermediate part of said link means are adapted to be pivotally connected together when required.

The said link means preferably comprises a pair of transverse links arranged respectively at the

front and back of the prop legs each such link being capable of being so arranged that it extends between and adjustably connects a corresponding prop leg to the central longitudinal member in order that the lower ends of the prop legs may be adjusted towards and from each other.

For this purpose the central longitudinal member may be provided with a longitudinally extending slot or with a series of adjustment holes to receive a pivot bolt for the inner ends of the said links.

Other features of the invention are hereinafter described.

In the drawings, which illustrate an exemplary form of the invention:

Figure 1 is a view in perspective of a step ladder in accordance with the invention.

Figure 2 is a view in vertical section of the upper portion of the ladder shown in Figure 1.

Figure 3 is a view in sectional plan of the prop and is taken on the plane indicated by the line 3—3 of Figure 1.

Figures 4 and 5 are views in rear elevation of the ladder and illustrate the prop members under different conditions of use;

Figure 6 is a view to a larger scale and shows the prop arranged in an alternative manner;

Figure 7 is a view in perspective showing a still further arrangement of the prop legs; and

Figures 8 and 9 are views in elevation and sectional side elevation respectively showing a modification of the invention.

The step ladder shown in the drawings has a front portion which is constructed in substantially the usual way—that is to say, it comprises a spaced pair of side members 10 supporting the ends of a plurality of transversely disposed steps 11. A transversely disposed board 12, hereinafter termed the "back board," of the kind commonly provided on step ladders, is secured rigidly to the rear faces of the upper ends of the side members and serves for the attachment of a hinged prop.

The prop includes a longitudinally disposed strut 13 secured at its upper end to a laterally extending board 14 which is connected by hinges 15 to the lower end of the back board 12, this strut being disposed in the central plane between the side members 10 of the front portion of the ladder. Thus the lower end of the strut 13 is movable towards and from said front portion in the usual way.

A lever 16 is pivotally connected at its center to the strut 13 somewhat below the lower edge of the board 14 and the upper ends of a pair of prop legs 17 are pivotally connected to the oppo-

site ends of this lever 16. These prop legs may normally diverge downwardly to some extent as shown in Figures 1 and 4.

The prop legs are also connected to each other some distance below the lever 16 by a spaced pair of transversely disposed links 18 and 19 which are arranged respectively at the back and front of the prop legs as shown in Figures 1 and 3 and are connected thereto by common detachable bolts 20 provided with wing nuts. Thus a lateral guide slot is formed by and between the spaced links, and the lower part of the strut 13 extends therethrough and normally is pivotally connected to the central parts thereof by a common removable bolt 21.

From the foregoing description it will be apparent that normally the prop legs 16 are capable of free longitudinal movements in opposite directions relatively to the strut 13. If, therefore, the front or stepped portion of the ladder is placed on a comparatively level surface and the prop legs placed on a comparatively uneven surface (as shown in Figure 4) the prop legs, by pivotal movements about the strut, will adapt themselves to inequalities in the supporting surface whereby the effective length of one prop leg becomes greater than the effective length of the other.

As this adjustment is effected automatically, a step ladder so constructed and used is quite stable and safe and obviates the need for using wedges or other packing means.

It is generally unnecessary to lock the prop legs in the adjusted positions as the ladder is quite stable when pivotal movements of the prop legs are not restricted.

By removing the aforesaid bolt 21 which normally connects the lower portion of the strut to the center of the pair of transverse links 18 and 19, the lower end of the strut is capable of swinging in the guide slot formed by and between these links. Thus, as shown in Figure 5, if the front stepped portion of the ladder is supported on an uneven surface so that the steps thereof incline to one side, the prop legs may be arranged to provide a stable support therefor.

In this connection it is to be noted that the links 18 and 19 maintain the strut 13 at all times in the common plane of the prop legs.

If desired, means may be provided for retaining the strut in its adjusted position when the ladder is arranged as shown in Figure 5. Thus, as shown by way of example in Figures 8 and 9, the lower end of the strut 13 may be fitted with a bracket 24 in which an adjustable clamping screw 25 is mounted.

The lower end of the prop may be prevented from spreading relatively to the front stepped portion of the ladder by any suitable means such as cords or other tie members which are commonly used for this purpose, and such member may be connected either to the lower end of the strut or to corresponding portions of the prop legs.

When the ladder is comparatively small, however, it is preferred to limit the angular movements of the strut by arranging the upper end of the board 14 to abut against the adjacent end of the back board 12 as shown in Figure 2.

There are many occasions when it is desirable to arrange the prop of a step ladder as close as possible to a reentrant corner such as the corner of a room, and for this reason the strut 13 is provided with a longitudinal slot 22 whereby the links 18 and 19 may be arranged in the al-

ternative manner shown in Figure 6 in which each link extends from one of the prop legs to the bolt 21 which latter for this purpose, is mounted in the slot 22. Thus, as shown in full lines in Figure 6, the lower ends of the prop legs may be arranged close together for the purpose referred to, while, should it be necessary under special conditions to increase the normal spacing of the prop legs, this may be accomplished by moving the bolt 21 downwardly in the slot 22 and by tightening same in the desired position of adjustment (see broken lines in Figure 6).

It will be noted that the lower end of the slot 22 is disposed well above the level of the bolts 20 in the prop legs, whereby the links 18 and 19 always incline upwards at a substantial angle to the bolt 21. Thus the bolt 21 (when tightened) can be moved freely upwards in the slot 22 merely by displacing the lower ends of the prop legs towards each other.

If desired, the slot 22 may be replaced by a series of adjustment holes.

Again, when the ladder is arranged close to a wall with the steps at right angles thereto, as shown in Figure 7, the links 18 and 19 may be arranged as shown in the figure whereby the inner prop leg is disposed substantially parallel to the strut while the outer prop leg diverges outwardly and downwardly therefrom at a substantial angle to provide increased lateral stability.

It will be evident that the invention is applicable to trestles and the like as well as to step ladders.

I claim:

1. A step ladder or the like having a front stepped portion and a supporting prop, said prop comprising a longitudinally disposed member, means pivotally connecting the upper end of the longitudinally disposed member to an upper part of the front portion, a cross member pivoted intermediate its ends to the longitudinally disposed member, a pair of prop legs arranged one at each side of the longitudinally disposed member and pivotally connected to said cross member, and link means spaced from said cross member and pivotally connected to the prop legs in such a manner as to form a transverse guide for the adjacent part of said longitudinally disposed member which is capable of relative lateral movements.

2. A step ladder or the like having a front stepped portion and a supporting prop, said prop comprising a longitudinally disposed member pivotally connected at its upper end to the front portion, a cross member pivotally connected intermediate its ends to an upper part of said longitudinal member, a pair of prop legs arranged one at each side of said longitudinal member, means pivotally connecting each prop leg to a corresponding part of said cross member, laterally extending link means arranged below said cross member, and means pivotally connecting said link means to said prop legs, said link means providing a transverse guide slot for the adjacent part of said longitudinal member.

3. A step ladder or the like having a front stepped portion and a supporting prop, said prop comprising a longitudinally disposed member hingedly connected at its upper end to the front portion, a cross member pivotally connected intermediate its ends to an upper part of the longitudinal member, a pair of prop legs arranged one at each side of said longitudinally disposed member, means pivotally connecting an upper

part of each prop leg to a corresponding part of said cross member, laterally extending link means arranged below said cross member and means pivotally connecting spaced portions of said link means to said prop legs, said link means forming a transverse guide for the adjacent part of said longitudinally disposed member, and means adapted to pivotally connect said longitudinally disposed member to said link means intermediate said prop legs while guided by the same, whenever desired. 10

4. A step ladder or the like having a front stepped portion and a supporting prop, said prop comprising a longitudinally disposed member hingedly connected adjacent its upper end to an upper part of said front portion, a cross member pivoted intermediate its ends to the longitudinally disposed member, a pair of prop legs arranged one at each side of the longitudinally disposed member and pivotally connected to said cross member, link means spaced from said cross member and pivotally connected to the prop legs, in such a manner as to form a transverse guide for said longitudinally disposed member, and means for optionally connecting said longitudinally disposed member to said link means at various alternative positions while guided by said link means. 15

5. A step ladder having a front stepped portion and a supporting prop, said prop comprising a longitudinally disposed member, means pivotally connecting an upper part of the longitudinally disposed member to an upper part of the front stepped portion of the ladder, a cross lever pivotally connected intermediate its ends to said longitudinally disposed member, a pair of prop legs arranged one at each side of said longitudinally disposed member and pivotally connected to said cross lever, and a pair of rigid links spaced from said lever and extending between and pivotally connecting the prop legs, said links being arranged respectively at the front and back of the longitudinally disposed member and forming guides therefor. 20

6. A step ladder having a front stepped portion and a supporting prop, said prop comprising a longitudinally disposed member, means pivotally connecting an upper part of the longitudinally disposed member to an upper part of the front stepped portion of the ladder, a cross lever pivotally connected intermediate its ends to an upper part of said longitudinally disposed member, a pair of prop legs arranged one at each side of said longitudinally disposed member and pivotally connected to said cross lever, and an opposed pair of transverse links arranged below the cross lever and extending between the prop legs, and common pivot members connecting the adjacent pairs of ends of the transverse links to the corresponding prop leg, said links being respectively arranged at the back and front of the longitudinally disposed member and forming guides therefor. 25

7. A step ladder having a front stepped portion and a supporting prop, said prop comprising a longitudinally disposed member, means pivotally connecting an upper part of the longitudinally disposed member to an upper part of the front stepped portion of the ladder, a cross lever pivotally connected intermediate its ends to said longitudinally disposed member, a pair of prop legs arranged one at each side of said longitudinally disposed member, a pair of rigid links spaced from said cross lever and extending between said prop legs, means pivotally connecting end por- 30

tions of said links to the respective prop legs, at least one end of one link being detachable from one of the prop legs and attachable to said longitudinally disposed member and the opposite end of the other link being detachable from the other prop leg and also attachable to said longitudinally disposed member and said links being arranged respectively at the front and back of the longitudinally disposed member and forming a guide therefor. 35

8. A step ladder or the like having a front stepped portion and a prop, said prop comprising a longitudinally disposed member provided with an apertured portion, a cross member pivoted to said longitudinally disposed member and extending from both sides thereof, a pair of prop legs arranged one at each side of the longitudinally disposed member and pivotally connected to corresponding portions of the cross member, and a pair of rigid links, one of said links having one of its ends pivotally connected to one of said prop legs at a point spaced from the said cross member, one end of the other link being similarly pivoted to the other prop leg and each of said links being additionally capable of alternative connection either to the opposite prop leg or to the said apertured portion of said longitudinally disposed member. 40

9. A step ladder or the like having a front stepped portion and a prop, said prop comprising a longitudinally disposed member provided with an aperture and pivotally connected adjacent its upper end to the adjacent part of said front portion, a cross lever pivotally connected intermediate its ends to said longitudinally disposed member, a pair of prop legs arranged one at each side of the longitudinally disposed member, each leg being pivotally connected to the corresponding end of said cross lever and a pair of links spaced from said lever, one end of one of said links being pivotally connected to one of said prop legs, the other link having one of its ends pivotally connected to the other prop leg and the remaining end of each link being capable of alternative connection either to the opposite prop leg or to the said longitudinally disposed member by means of said aperture in the latter, said links, when arranged to extend between and connect the pair of prop legs, being arranged respectively at the front and back of the longitudinally disposed member and forming a guide therefor. 45

10. A step ladder or the like having a stepped front portion and a prop, said prop comprising a longitudinally disposed member having a slotted portion and pivotally connected adjacent its upper end to the adjacent part of said front portion, a cross lever pivotally connected intermediate its ends to said longitudinally disposed member, a pair of prop legs arranged one at each side of the longitudinally disposed member, each leg being pivotally connected to the corresponding end of said cross lever and a pair of links spaced from said lever, one end of one of said links being pivotally connected to one of said prop legs, the other link having one of its ends pivotally connected to the other prop leg and the remaining end of each link being capable of alternative connection either to the opposite prop leg or to the said slotted portion of longitudinally disposed member, said links, when arranged to extend between and connect the pair of prop legs, being arranged respectively at the front and back of the longitudinally disposed member and forming a guide therefor, 50

and means adapted to connect said longitudinally disposed member and at least one of said links pivotally together intermediate said prop legs when said links extend between and are pivotally connected at their opposite ends to the prop legs.

11. A step ladder or the like having a front stepped portion and a prop, said prop comprising a longitudinally disposed member provided with a longitudinally slotted portion and pivotally connected adjacent its upper end to the adjacent part of said front portion, a cross lever pivotally connected intermediate its ends to said longitudinally disposed member, a pair of prop legs arranged one at each side of the longitudinally disposed member, each leg being pivotally

connected to the corresponding end of said cross lever, a pair of links spaced from said lever, one end of one of said links being pivotally connected to one of said prop legs, the other link having one of its ends pivotally connected to the other prop leg, and connecting means at the remaining end of each link adapted to connect the same alternatively either to the opposite prop leg or to said longitudinally slotted portion of said longitudinally disposed member, said links, when arranged to extend between and connect said pair of prop legs, being arranged respectively at the front and back of the longitudinally disposed member and forming a guide therefor.

JOHN ALLAN.
